DESIGN FOR A HAND MIRROR FRAME

Joseph Casalino, Forest Hills Gardens, Long Island, N. Y., assignor to Dieplast Corporation, New York, N. Y., a corporation of New York

Application November 28, 1945, Serial No. 124,124

Term of patent 3½ years

(Cl. D86—10)

To all whom it may concern:

Be it known that I, Joseph Casalino, a citizen of the United States, residing at Forest Hills Gardens, in the county of Queens and State of New York, have invented a new, original, and ornamental Design for a Hand Mirror Frame, of which the following is a specification, reference being had to the accompanying drawing, forming a part thereof.

Fig. 1 is a front elevational view of a hand mirror frame showing my new design;

Fig. 2 is a side elevational view thereof;

Fig. 3 is an end elevational view of the handle

end of the mirror frame, omitting the background;

Fig. 4 is a cross-section on the line 4—4 of Fig. 1; and

Fig. 5 is a cross-section on the line 5—5 of Fig. 1.

I claim:

The ornamental design for a hand mirror frame, as shown.

JOSEPH CASALINO.
